LOW-FREQUENCY SIGNALING

Harmon E. Deal, Glen Ridge, N. J., assignor to
Radio Corporation of America, a corporation of
Delaware

Application December 5, 1942, Serial No. 467,925

1 Claim. (Cl. 177—353)

My present invention relates to low frequency signaling systems, and more particularly to warning systems of the so-called "alert" type.

In my application Serial No. 403,736, filed July 23, 1941, Patent No. 2,340,798, dated February 1, 1944, I have disclosed, and claimed, a system for modulating a radio frequency carrier with a low control frequency, radiating the resultant modulated carrier to a remote receiver equipment, and causing the low control frequency energy at the receiver to actuate an alarm circuit-closing device and concurrently to render the receiver reproducer ineffective. A change in low frequency at the transmitter causes the alarm device to be ineffective while simultaneously energizing the reproducer. At the receiver, there are employed highly selective reeds which are tuned to respective low frequencies. These reeds are utilized for the aforesaid control functions.

Now, I have invented a method of utilizing carrier energy modulated by low modulation frequencies in a system for transmitting complete coded messages, and the reeds of the control network at the receiver equipment being visually observed for the message. In accordance with my present system, a plurality of reeds of different resonant frequencies are arranged to be selectively actuated by a common driving source. Certain of the reeds function as message-indicators, while other reeds act as call control switches.

These, and other, objects of my invention will be described in detail in the following specification, it being pointed out that a more specific object of the invention is to improve the efficiency of radio signaling systems employing low control modulation frequencies.

The novel features which I believe to be characteristic of my invention are set forth with particularity in the appended claim; the invention itself, however, as to both its organization and method of operation will best be understood by reference to the following description taken in connection with the drawing in which I have indicated diagrammatically a circuit organization whereby my invention may be carried into effect.

In the drawing:

Fig. 1 shows a receiving system which embodies the invention.

Fig. 2 illustrates the appearance of the viewing ends of the reeds.

Referring, now, to the accompanying drawing, wherein like reference characters in the two figures designate similar elements, the numeral 1 indicates, in general, a signal collector of any

desired type. The collector may be a dipole where the modulated carrier wave energy lies in the megacycle range. On the other hand, the collector may be a grounded antenna circuit, or a radio frequency distribution line. As explained in my aforesaid patent application, at the transmitter the carrier energy may be modulated with the usual voice, or music, modulation material. However, when it is desired to utilize the auxiliary signaling system to be described at a later point, one or more low modulation frequencies may be applied to the carrier. These low modulation frequencies may lie in a range of 10 to 50 cycles, although the invention is not restricted to these particular frequencies. In my aforesaid application there is disclosed one method of generating various low modulation frequencies, and it is to be understood that the method disclosed in that application may be applied to the transmitter in the present system. I have not shown such a transmitter, because any form of transmitter well known in the art may be utilized. To preserve simplicity of description, it is assumed that four low modulation frequencies, lying in a range of 20 to 40 cycles, will be used in the present system.

According to my present invention, certain of these low modulation frequencies are to be used as message-representative signals, while others of the low frequencies are to be employed as calling frequencies. By way of specific example, let it be assumed that the 20 and 30 cycle frequencies are to be used for calling purposes, while the 36 and 24 cycle frequencies are to be employed to convey a message. In such case, one or more of these four low modulation frequencies will be applied to the carrier at the transmitter, and then radiated to the various signal collectors.

The signal collector 1 is connected to the input terminals of a radio receiver 2 of any desired construction. The receiver may be of the superheterodyne form, or of the tuned radio frequency amplifier form, or even of the super-regenerative type. The receiver is schematically represented, since it is only the audio output circuit of the receiver which is of interest in connection with my present invention. Let it be assumed, therefore, that the numeral 3 designates the audio transformer which feeds the audio frequency energy of the receiver to the audio amplifier output stage 4. As is noted, the amplifier stage 4 is of a conventional type, and its output transformer 5 will be understood as being connected to the voice coil of the usual loud

speaker. Thus far there has been described a conventional and normal type of receiving system.

In order to secure a response to the low modulation frequencies, the energy of the latter is filtered off from the main audio channel at some point prior to the voice coil of the loud speaker. For example, let it be assumed that the low frequency modulation energy is taken off from the grid circuit of amplifier 4, and that the energy is applied through the condenser 6 to a filter 7. The filter 7 is constructed to pass the low frequencies. This filter, for example, may be a low pass filter which has a cut-off at approximately 100 cycles. Such a filter is easily constructed, and would obviously prevent modulation frequencies other than those in the low frequency range from passing to the reed-control circuit.

The reeds are driven by electromagnet 8 whose winding is arranged in the plate circuit of the amplifier tube 9. Here, again, the amplifier 9 may be of a conventional form, and its grid circuit is shown as including a negative biasing source for the grid of the tube. The grid itself is coupled through a direct current blocking condenser 10 to the output terminals of the low pass filter 7. It will be understood that the amplifier 9 will amplify those of the low modulation frequencies which were applied to the carrier at the transmitter.

According to my invention, I utilize a common support, or mounting, for the four selective reeds. The reeds are indicated by the reference letters A, B, C and D. These four reeds are mechanically resonant to 20 cycles, 30 cycles, 36 cycles and 24 cycles respectively. As is well known to those skilled in the art, each reed consists of thin spring steel. Each reed has one end thereof secured in a metal base 11. The base, in turn, is securely fastened to a substantially L-shaped armature 12. The appearance of the armature is shown in Fig. 1, and it will be noted that the vertical section of the armature has an extensive portion 13 which is positioned adjacent the core of the electromagnet 8.

The armature 12 is metallic, and is composed, of course, of a magnetic material. The horizontal section of the armature supports the various bases 11 of the reeds. However, each reed extends substantially beyond the forward edge of the horizontal section of the armature. A steel spring support 14 is rigidly secured to the vertical section of armature 12. The steel spring support 14 may be secured to a horizontal wooden backing 15, if desired. The steel spring support 14 is grounded through a resistor 16 of relatively small magnitude, say for example 20 ohms, while each of reeds A and B is provided on its lower face, adjacent its free end, with a contact point. The contact point of each reed A or B is adapted to cooperate with a second contact point thereby to provide a switch which closes only when a particular reed vibrates in resonance with an applied low modulation frequency.

The numeral 20 indicates the contacts associated with reed A, and the numeral 20' indicates the contacts associated with reed B. The reeds C and D need not have contacts associated therewith, since they function as message-representative indicators. The contacts 20 are connected to a further switch contact 21, while the contacts 20' are connected to a switch contact 22. The adjustable arm T is provided for making contact with either of 21 or 22. In other words, contact arm T functions to select which of the calling

reeds is to be capable of energizing the calling device. When the switch arm T makes contact with point 21, then the calling device will only operate when a 20 cycle modulation frequency exists on the carrier. On the other hand, the calling device will only be operative for the 30 cycle modulation frequency when contact arm T is electrically connected to point 22.

The arm T is connected by lead 30 to one end of the winding of electromagnet 31. The lower end of the winding is connected to the positive terminal of a direct current source 32' whose negative terminal is grounded. The winding of electromagnet 31 is by-passed for alternating current by condenser 32. It will, therefore, be seen that current will flow through the winding of electromagnet 31 when switch arm T is on either of 21 or 22, and when the respective reed contacts 20 or 20' are closed.

Upon energization of the electromagnet 31 a switch 40, which is normally spring-biased to open position, is closed. In circuit with the switch 40 there is included an indicator device, such as an incandescent lamp 50, a direct current energizing source 51, and a switch 52. The switch 52 is provided so that the operator may manually open the indicator circuit, if such opening is desired. This, of course, will render the signaling circuit completely inoperative so long as switch 52 is open. Assuming that the switch has been closed, energization of electromagnet 31 with consequent closing of switch 40 is necessary to cause indicator lamp 50 to burn. Of course, the lamp 50 may be replaced by an audible signaling device, such as an electric bell. In general, my invention is not restricted to any particular type of calling circuit or calling device.

In Fig. 2 I have shown the appearance of the free ends of the reeds A, B, C and D, as well as the visual indicator 50. The free end of each reed may be provided with a colored tab, as indicated by numeral 66 in Fig. 2. These tabs may be colored white so that when a reed vibrates violently the effect of a continuous white band will be produced. This effect is indicated by the dotted rectangle 61 in Fig. 2. It will be obvious that the reeds may be enclosed in a casing having a window, and that the reeds may be positioned horizontally in the casing. The free ends of the reeds may be viewed through the window. The casing may, also, have a portion thereof constructed so that the indicator lamp 50 can be viewed therefrom.

To explain the operation of the system, let it be assumed first that the receiver is positioned in the home of an individual, such as an air raid warden, whose calling letter is A. This means that he will adjust his switch arm T to point 21. When reed A vibrates in response to the reception of a 20 cycle modulation frequency, then the electromagnet 31 will cause switch 40 to be closed. This indicates visually at lamp 50 that a call is being sent through for A to be on the alert for a possible message to follow. Of course, another warden might have the call letter B, and he would then have his switch T adjusted to point 22. Obviously, as many call reeds as desired could be provided on the armature 12. In that case each call reed would have its own low modulation frequency.

The reed driving armature 13 is pulled back and forth by electromagnet 8 when there flows through the winding of the latter the currents of the various low modulation frequencies. If there exists a 20 cycle current in the output of

filter 7 then armature 13 will be actuated. However, the only reed that will vibrate violently in response to the 20 cycle frequency will be reed A. Reeds B, C and D will not vibrate with any substantial amplitude, because they are highly selective. These other reeds will merely move as part of the general armature assembly. Assume, now, that there exists in the winding of electromagnet 8 modulation frequencies of 20 cycles and 30 cycles. In that case the light 50 will burn at the positions of the A individuals, and the A reed will have its free end simulate the dotted rectangle 61. On the other hand, at the locations of the B individuals it will be the free end of the B reed which will simulate the dotted rectangular pattern, while the visual indicator at these positions will be active.

After the calling reed has been actuated, there may now be applied at the transmitter the C and/or D modulation frequencies. Let it be assumed that C and D reeds are to be actuated by applying concurrently the 36 cycle modulation and 24 cycle modulation to the carrier. In such case there will flow through the winding of electromagnet 8 the currents of both these modulation frequencies, and this will cause violent vibration of both reeds C and D. The observer will then see both free ends of these reeds simulate the rectangular pattern. They will then know, in accordance with a predetermined code, that a certain message has been sent to them. It is to be understood that subsequent to the calling signal, there will be included that particular calling-reed as part of the message signals along with reeds C and D.

In other words, assume that the 20 cycle modulation frequency has been transmitted so as to call all individuals A to stand by for messages. Thereafter, the 20 cycle frequency can be used in conjunction with the 36 and 24 cycles so as to provide messages by means of the vibrations of reeds A, C and D. This would also be true for the B reed. It will, therefore, be seen that after transmission of a call frequency, rather complete coded messages can be sent by visual observation of the reeds. For example, after calling individuals A, reeds A, C and D simultaneously vibrated could mean: "Stand by for further

instructions"; reeds C and D vibrated concurrently could mean another instruction; reeds A and D vibrated simultaneously could mean a further instruction. Finally, vibration of D by itself could mean that the system could be turned off, or that it was an "All clear" signal.

It will be understood that actuation of switch 40 may, if desired, render the circuit to the voice coil ineffective. The utility of such arrangement would reside in the fact that interruption of sound reproduction would focus attention on the reeds and indicator. Preferably, however, it is desired to keep the sound channel continually clear so that instructions can readily be given to the called individuals. Of course, the codes of signals can be changed periodically. Indeed, at periodic intervals the message reeds could be changed over to function as call reeds, while the reeds A and B could function as message reeds. The circuit changes required for such an interchange are obvious.

While I have indicated and described a system for carrying my invention into effect, it will be apparent to one skilled in the art that my invention is by no means limited to the particular organization shown and described, but that many modifications may be made without departing from the scope of my invention, as set forth in the appended claim.

30. What I claim is:

In a reed signaling system, a plurality of reeds of different frequencies, a common magnetic support for said reeds, said magnetic support having an extension, a source of currents of frequencies corresponding to said reed frequencies, an electromagnet responsive to the currents for actuating said support extension thereby to vibrate solely those reeds corresponding in frequency to the frequencies of the said currents, 40 an indicator circuit including a normally open switch, a control circuit for the switch including an electromagnet positioned adjacent the normally open switch to actuate the latter upon energization of the control circuit, and switch 45 means for selectively associating desired ones of said reeds to act as a control circuit-closing device.

HARMON B. DEAL.
